HEEL SAVER FOR SHOES

Clarence R. Hanus, Milwaukee, Wis.

Application May 13, 1939, Serial No. 273,445

3 Claims. (Cl. 36—75)

This invention relates to heel savers for shoes.

An object of this invention is to provide a heel for a man's or woman's shoe having means to prevent the heel from wearing away too quickly and to insure a degree of uniformity of wearing.

A further object of this invention is to provide a heel for a shoe having a screw threaded longitudinal opening with coarse threads and a collar screwed therein and having an axial screw threaded opening receiving a screw to contact the ground, the inner screw being adjustable as it wears to compensate for wearing, the screws being replaceable when worn away.

A still further object of this invention is to provide in a heel of the character described, coarse left hand threads on the outside of the collar, and standard right hand threads for the inner screw, so that as the inner screw is unscrewed, the outer collar will not be unscrewed therewith.

Still another object of this invention is to provide a strong, compact and durable heel construction of the character described, which shall be relatively inexpensive to manufacture, easy to adjust, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention,

Fig. 1 is a side elevational view of a portion of a man's shoe provided with a heel, embodying the invention;

Fig. 2 is a bottom plan view of the heel shown in Fig. 1;

Fig. 3 is a perspective view of the key for unscrewing the collar shown in Fig. 1;

Fig. 4 is a perspective view of a key used to unscrew the inner screw;

Fig. 5 is a perspective view of an inner screw with a hexagonal wrench opening;

Fig. 6 is a perspective view of a wrench for unscrewing the screw shown in Fig. 5;

Fig. 7 is a side elevational view of a lady's shoe with a heel, embodying the invention; and

Fig. 8 is a bottom plan view of the heel shown in Fig. 7.

Referring now in detail to the drawing, 10 des-

ignates a shoe here shown as a man's shoe, provided with a heel 11 embodying the invention. The heel 11 may be made of leather or any other suitable material and is formed with a plurality of vertical, spaced, screw threaded openings 12. 5 The threads of the screw threaded openings 12 may be coarse and are preferably left handed threads.

Screwed within each opening 12 is a collar or tube 14, having outer threads 15 receiving the 10 threads of the openings 12. The tubes 14 are of such length as to stop short of the bottom surface 16 of the heel 11, so as not to contact the ground. Said tubes are each formed with an internally screw threaded axial opening 17, preferably having standard screw threads to receive a screw 18 of uniform diameter. The lower end of the screw 18 is flush with the under-surface of the heel 11.

The threads of the threaded opening 17 are 20 right handed threads, so that as the screw 18 is unscrewed, the collar 14 will be tightened within the heel and will not be unscrewed therewith.

The lower end of the collar 14 may be formed with four notches 20 at right angles to one another, so that the same may be unscrewed by a key 21 shown in Fig. 3, and having four wings 22 adapted to be received within the notches 20.

The lower end of the screw 18 may be formed with a longitudinal slot 24, and may be unscrewed 30 by a key 25 having a blade 26 adapted to be received within the key slot 24.

Preferably only the screw contacts the ground, and as the same wears the wear may be compensated by unscrewing the screw. The slot 24 35 is therefore preferably of considerable length, so as to get more wear out of the screw. The screws 18 may be replaced when worn away.

If desired the slot 24 may extend all the way through the screw 18, so that more wear can be 40 obtained with said screw.

In Fig. 5 there is shown a screw 18a, similar to the screw 18, but having a hexagonal opening 30. In Fig. 6 there is shown a wrench 31 which may be used to unscrew the screw 18a from the 45 collar 14. The opening 30 may also extend all the way through the screw 18a, so as to permit use of the screw 18a for longer periods.

In Fig. 7 there is shown a lady's shoe 35, provided with a heel 36 having a tread portion or 50 lift 37. The lift 37 is provided with screw threaded openings 12 to receive the collars 14 and the inner screws 18, as shown in Figs. 1 and 2 of the drawing.

It will thus be seen that there is provided a 55

device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. A heel having a vertical screw threaded opening, a member screwed within said opening, 15 and having an internally screw threaded opening therein, and a screw screwed within said internally screw threaded opening, the external screw threads of the tubular member being coarser than the threads of the internally screw 20 threaded opening, and extending in a direction opposite to the threads of said internally screw threaded opening.

2. A heel having a vertical screw threaded opening, a member screwed within said opening, 25 and having an internally screw threaded opening therein, and a screw screwed within said

internally screw threaded opening, the external screw threads of the tubular member being coarser than the threads of the internally screw threaded opening, and extending in a direction opposite to the threads of said internally screw 5 threaded opening, said tubular screw threaded member terminating short of the bottom surface of the heel, and the lower end of said screw being flush with the under-surface of said heel.

3. A heel having a vertical screw threaded 10 opening, a member screwed within said opening, and having an internally screw threaded opening therein, and a screw screwed within said internally screw threaded opening, the external screw threads of the tubular member being 15 coarser than the threads of the internally screw threaded opening, and extending in a direction opposite to the threads of said internally screw threaded opening, said tubular screw threaded member terminating short of the bottom surface 20 of the heel, the lower end of said screw being flush with the under-surface of said heel, the lower end of said tubular member having notches to receive a wrench, and the lower end of said screw having a wrench opening.

CLARENCE R. HANUS.
